UNITED STATES PATENT OFFICE.

ANSON J. BACON, OF HALLOWELL, MAINE.

DESIGN FOR A PENCIL.

SPECIFICATION forming part of Design No. 32,728, dated May 29, 1900.

Application filed March 8, 1900. Serial No. 7,936. Term of patent 14 years.

To all whom it may concern:

Be it known that I, ANSON J. BACON, a citizen of the United States, residing at Hallowell, in the county of Kennebec and State of Maine, have invented a certain new and useful Design for Pencils, of which the following is a specification.

This invention is a design for pencils, and the novelty thereof resides in the peculiar shape and ornamentation of the device, as will be fully described hereinafter, and illustrated in the accompanying drawing, in which the figure represents a front elevation of the design.

The pencil as illustrated comprises a body portion 1, tapering from one end to the other—that is to say, one end is of greater diameter than the other—to represent a cannon. At the end having the greatest diameter is designed

the representation of a human head 2, while immediately below the head is the representation of a battle-ship 3 against a suitable background. A United States flag 4 is also arranged upon the surface of the pencil, with the stars 5 suitably grouped and the strips 25 running parallel with the sides of said pencil, as at 6. The remaining portion of the surface of the pencil is smooth.

What I claim, and desire to secure by Letters Patent, is—

The design for a pencil substantially as shown and described.

In testimony whereof I affix my signature in presence of two witnesses.

ANSON J. BACON.
